UNITED STATES PATENT OFFICE.

JOHN EDWARD LEVASSEUR, OF MONTICELLO, IOWA, ASSIGNOR TO GREEN-LIEF W. SIMPSON, OF SOMERVILLE, MASSACHUSETTS.

BUTTER-CAN.

SPECIFICATION forming part of Letters Patent No. 380,211, dated March 27, 1888.

Application filed January 21, 1888. Serial No. 261,446. (No model.)

To all whom it may concern:

Be it known that I, JOHN EDWARD LEVASSEUR, a citizen of the United States, and a resident of Monticello, in the county of Jones and State of Iowa, have invented new and useful Improvements in Butter-Cans, of which the following, taken in connection with the accompanying drawings, is a specification.

This invention relates to improvements in butter-cans for the purpose of hermetically sealing butter for transportation or otherwise; and it is particularly designed and constructed in such a manner that the butter can be packed in the can and the cover soldered to its top, to the exclusion of any air between the butter and the sink-cover, as will hereinafter be more fully shown and described.

The invention is for the same purpose as that shown and described in the Letters Patent No. 205,309, granted June 25, 1878, to Green-lief W. Simpson, and is an improvement on the can shown and described in said Letters Patent.

In the drawings, Figure 1 represents a plan view of my improved butter-can, and Fig. 2 represents a partial side elevation and longitudinal section of the same.

Similar letters refer to similar parts wherever they occur on the drawings.

30 In packing butter in tin cans it is of the utmost importance that all the air should be excluded from within the can when filled and when the cover is soldered to its top, so as to keep the butter pure and sweet for an indefinite length of time, and to accomplish this I construct my improved can as follows:

a is the cylindrical can, and *a'* is its upper annular edge, which is preferably made by being bent outward upon itself and against the outside of the top of the can, as shown in Fig. 2, so as to form an increased thickness at such upper edge; but this may, if so desired, be accomplished by soldering a band around the outside of the top of the can without departing from the essence of my invention. To the outside of the upper annular edge, *a'*, is soldered the metal band *b*, having in its upper end an outwardly-flaring edge, *b'*, in the same manner as shown and described in the 45 Simpson patent above mentioned.

c is the sink-cover, the upper portion of which is adapted to fit snugly within the metal band *b*, as shown in Fig. 2, and said cover has in its upper end an outwardly-flaring edge, *c'*, between which and the flaring edge *b'* of the band *b* is left a space sufficient to receive the molten solder *d*, by means of which the band *b* and said cover are hermetically sealed together after the can is filled.

The sink-cover *c* has at *c''* an offset adapted to rest on the upper edge of the can *a*, and below such offset the sink-cover has a reduced portion, *c''*, adapted to fit snugly within the top of the can *a*, as shown in Fig. 2.

In using the can the metal band *b* is soldered to the outside of the upper portion of the said can *a*, as shown in Fig. 2. The can is then filled with butter up to near its top, after which the sink-cover is introduced within the top of the can until the bottom of said cover rests on the butter within the can and the annular offset *c''* of the sink-cover rests against the top of the can, as shown in Fig. 2. During such insertion and depression of the sink-cover any air that may exist within the upper part of the can is forced upward between the outside of the sink-cover and the interior of the metal band *b*, after which the flaring edges *b' c'* of the upper portions of the metal band *b* and sink-cover *c*, respectively, are united and secured hermetically together by means of the molten solder *d*, as shown in Fig. 2, and in this manner no air is allowed to remain within the can, to the injury and detriment of the butter.

When it is desired to open the can, all that is necessary to do is to strip off the metal band *b*, by which the solder *d* is broken, after which the sink-cover *c* may be raised with ease, and after any portion of the butter has been removed the cover may be replaced in its original position from time to time, as may be required.

Having thus fully described the nature, construction, and operation of my invention, I wish to secure by Letters Patent, and claim—

The herein-described butter-can, having the metal band *b* soldered to its upper portion, said band having an outwardly-flaring edge, *b'*, in its upper end, combined with the sink-cover *c*,

adapted to fit the interior of the band *b*, and having an offset, *c''*, adapted to rest on the top edge of the can, a reduced lower portion, *c'*, adapted to fit the interior upper portion of the can, and an upper flaring edge, *c'*, adapted to be united to the band *b* and its flaring edge by means of solder or alloy *d*, as and for the purpose set forth.

In testimony whereof I have signed my name to this specification, in the presence of two subscribing witnesses, on this 13th day of January, A. D. 1888.

JOHN EDWARD LEVASSEUR.
